US00D474101S

(12) **United States Design Patent** (10) Patent No.: **US D474,101 S**
 Simon et al. (45) Date of Patent: ** May 6, 2003

(54) **LATCH PROTECTOR FOR CYLINDRICAL DOOR LOCK**

(75) Inventors: **Ira J. Simon**, Long Beach, CA (US);
Martin S. Simon, Long Beach, CA (US)

(73) Assignee: **Triangle Brass Manufacturing Company, Inc.**, Los Angeles, CA (US)

(**) Term: **14 Years**

(21) Appl. No.: **29/156,793**

(22) Filed: **Mar. 6, 2002**

(51) LOC (7) Cl. **08-07**

(52) U.S. Cl. **D8/346**
